INKING SYSTEMS FOR OFFSET PRINTING AND DUPLICATING MACHINES

Erich Gericke, Flemmingstrasse 14,
Berlin-Steglitz, Germany

Filed Apr. 20, 1959, Ser. No. 807,533

Claims priority, application Germany Oct. 31, 1958
5 Claims. (Cl. 101—351)

This invention relates to inking systems for offset printing and duplicating machines in which the inking system comprises rollers so arranged that each alternate roller is mounted in a common frame which can be tilted into the required position by means of a hand lever. When printing is completed such inking system are placed into an "inoperative position" to permit the rollers to be moved for cleaning or other purposes.

Printing and duplicating machines are already known in which the inking system is controlled in the following manner: In order to place the inking system into "inoperative position," that is to say in order to raise the inking frame and to place it against an upper limit stop, a control lever must first be placed in the "off" position. Two catch levers must then be moved into a position in which they will release the tiltable frame. The latter can then be tilted into "inoperative position" by raising it by means of handles or levers. To perform this operation the actuation of five levers is therefore required.

Even skilled and experienced personnel find this complicated and time wasting. Nor does the arrangement comply with the requirements that progressive and modern printing and duplicating machines might be expected to fulfill.

The arrangement according to the present invention, differs from known arrangements in that it substantially simplifies the manipulation of the inking system and also economises in the number of structural elements that are required. The entire above-described operation of placing the inking system into "inoperative position" is now reduced to a single manipulation. The arrangement according to the present invention comprises only one lever which is provided with a forked member adapted slidably to engage a guide pin and thereby to retain the inking roller frame in the correct position for use. When printing operations have been completed, this lever is placed into an "off" position and by this movement the lever tiltably raises the inking roller frame into the "inoperative position."

To prevent the control lever from being accidentally displaced out of its existing position on the inking roller frame, or from slipping when the inking roller frame is raised, a safety device is provided on the opposite side of the inking system which prevents the control lever from being displaced once the forked member ceases to be in engagement with its co-operating guide pin.

During operation of the machine, a catch mounted on the inking roller frame is retained in a position which permits the inking control lever to be pivotally deflected and operated. As soon as a second forked member becomes disengaged from its guide pin, the catch is released by a lever and a pin and automatically locks the control lever shaft in position.

A controlling operation by deflection of the control lever cannot therefore be performed unless the guide pin is engaged by the forked member, whereas the control lever and the inking roller frame form a rigid unit when the inking roller frame is raised. Should the catch fail to lock the control shaft, an abutment on the machine wall is so arranged as to prevent the inking roller frame from being raised. In other words, the several operations of controlling, locking, and raising the inking system are all performed with the aid of one control lever.

2

The advantage afforded by the present invention resides in that the mechanism is greatly simplified and structural elements are reduced to a minimum and that the operation of the machine is greatly facilitated.

5 A preferred embodiment of the invention will now be hereinafter described by way of example with reference to the accompanying drawings, in which:

FIG. 1 shows in schematic form an offset printing machine with the inking system in the "off" position;

FIG. 2 is a plan view of the inking system;

FIG. 3 is a side view of the inking system with the control lever in "printing" position;

FIG. 4 is a side view of the inking system with the control lever in the "off" position;

15 FIG. 5 shows the inking roller frame in raised position, and

FIG. 6 is a side view of a safety mechanism for locking the control lever shaft in position.

20 In offset printing and duplicating machines the sheets are arranged in a stack maintained with its top sheet at a constant level by a feeler device controlling the height of a table upon which the stack rests. The sheets must be fed to the printing position one by one, and each sheet is detached from the stack by a blowing device raised by 25 suckers, and conveyed between forwarding rollers to front and side lays for alignment thereby. A bail keeps the sheets flat and prevents them from buckling. When the sheets have been brought into register, the front edge of each sheet is abruptly picked up by grippers on a revolving impression cylinder. The sheet then passes between 30 blanket and impression cylinders from which it receives the impression. All the rotating parts of the machine are driven by an electric motor, and the printing speed and operational rhythm of the machine can be controlled by a continuously variable transmission.

35 The impression is transferred to the sheets from an inked and damped foil on a plate cylinder by a blanket on the blanket cylinder. The feeding, distribution, and 40 application of ink to the printing foil is effected by an inking system, comprising a fountain, a fountain roller, a fountain feed roller, and inking and rubbing down rollers. The three inking rollers (one inking and two transfer 45 rollers) are mounted in a common tiltable frame and are moved into operative position by tilting the frame about its fulcrum. The inking system is provided with control means which are independent of the other operating parts of the machine. The several control positions have the following functional effects:

40 I. Separation of the several rollers when in idling position (position of rest),

II. Contact between the several rollers to provide all the rollers evenly with ink and damping fluid before the actual printing operation begins.

55 III. Contact between the two transfer rollers, the rubbing down rollers, and the printing foil for transferring the ink to the same.

When the printing operation is completed and the inking system is stopped, the inking roller frame must be 60 raised to permit the rollers to be cleaned or replaced and to give access to components inside the machine.

65 Stopping of the inking system and raising of the tiltable roller frame 1 is effected by operating a control lever 2 (FIGS. 1, 2 and 3). Three or four alternative control positions of the inking system are established by the insertion of a pin 3 on the control lever 2 into one of a number of grooves in an arresting quadrant 4. A leaf spring 5 retains lever 2 in position. The end of lever 2 is provided with a forked member 6 which slides on a 70 pin 7 secured to a side wall of the machine and permits the position of the inking roller frame to be varied. Before the frame is raised the inking system control lever

2 must be placed in the "off" position (FIG. 1). This causes the frame **1** to be pushed upwards by the co-operation of the slot in the forked member **6** of the control lever and the fixed guide pin **7**, so that the inking rollers **8** to **12** are separated (FIG. 4).

By means of the control lever **2**, the roller frame **1** can now be tiltably raised until the frame is retained by an abutment **13** on a wall **23** of the machine (FIG. 5). To prevent accidental displacement or disengagement due to careless handling of the control lever **2**, a safety catch is provided on the side of the frame remote from that which carries the control lever. When the forked member **6** is released from guide pin **7**, the control shaft **14** is locked in position by engagement of a pin **15** with a catch **16**.

A trip lever **17** mounted on the inking roller control shaft **14** carries a stud **19** which upon disengagement of a forked member **6'** from a guide pin **7'** releases the catch **16** permitting it to be tilted by a spring **18** in such manner that pin **15** on control shaft **14** engages a recess in the catch and thus locks the control shaft **14** in position.

Catch **16** and spring **18** are mounted on a pin **20** fitted to a wall of the tilttable inking roller frame **1**. The catch **16** acts on trip lever **17** by bearing on the stud **19**. The deflection of lever **17** is limited by a hole **21** (FIG. 6), into which a pin **22** on forked member **6'** projects. To prevent the roller frame **1** from being raised otherwise than in the locked position the frame **23** of the machine is provided with an abutment **24** which blocks catch **16** if this is not in locking position when the roller frame is raised.

I claim:

1. In a printing machine having an inking system the combination comprising a frame, a roller frame pivotally mounted in said frame, a plurality of inking rollers, each alternate inking roller being mounted in said frame and the other inking rollers being mounted in said roller frame, a guide pin on said frame, and a control lever on said roller frame having a forked member cooperating with said guide pin for moving said roller frame to various positions, said forked member being disengageable

from said guide pin in one position of said lever to permit movement of said roller frame to an inoperative position.

5 2. A printing machine according to claim 1 wherein a safety device cooperates with a second guide pin for preventing said control lever from being moved when said forked member becomes disengaged from its cooperating guide pin.

10 3. In a printing machine having an inking system the combination comprising a frame, a roller frame pivotally mounted in said frame, a plurality of inking rollers, each alternate inking roller being mounted in said frame and the other inking rollers being mounted in said roller frame, a guide pin on said frame, a control lever on said 15 roller frame for moving said roller frame to various positions where it may be locked in position by said guide pin, a forked member on said control lever cooperating with said guide pin, a shaft connected to said control lever, a trip lever on said shaft, a stud on said trip lever, a second pin on said shaft, a catch in engagement with said 20 second pin which is released when said forked member slides on its cooperating guide pin, and means whereby on disengagement of said forked member and said guide pin, said catch engages said second pin on said shaft and locks said shaft in position.

4. A printing machine according to claim 3, wherein a spring acts on said catch and moves said catch into a position in which said shaft is locked by said catch engaging said second pin.

30 5. A printing machine according to claim 3 wherein an abutment is provided on said frame to block movement of said control lever when said catch fails to engage said shaft.
